UNITED STATES PATENT OFFICE

JAMES M. KEPLAR, OF ELKHART, INDIANA

FILING SYSTEM

Application filed March 11, 1931. Serial No. 521,861.

This invention relates to a filing system and has for its primary object to provide, in a manner as hereinafter set forth, a filing system including a plurality of index cards and a holder having novel coacting means for removably supporting the cards in overlapping relation in order that a marginal portion of each card may be exposed for index purposes.

10 A further object of the invention is to provide a filing system of the character aforesaid, wherein each card is provided adjacent the top thereof with a hinge line to enable the same to be folded when desired in order to expose the body of the adjacent card therebeneath and the back of the card so folded.

With the foregoing and other objects in view, the invention consists of the novel construction, combination and arrangement of 20 parts as hereinafter more particularly described and shown in the accompanying drawings, but it is to be understood that the description and drawings are to be considered as illustrative rather than limitative.

25 In the accompanying drawings in which like numerals are employed to designate like parts throughout the several views:

Figure 1 is a view showing in front and rear elevation respectively, a pair of holders, 30 each having a plurality of cards supported thereon.

Figure 2 is a side elevation of the embodiments shown in Figure 1.

Figure 3 is an elevation of one of the cards 35 shown in Figure 1.

Figure 4 is a fragmentary elevation of one of the holders shown in Figure 1.

Figure 5 is an enlarged fragmentary vertical section showing one of the holders and 40 cards supported thereon.

Figure 6 is a fragmentary front elevation showing a plurality of cards of a modified form supported on a holder.

Referring to the drawing in detail, more 45 particularly to Figures 1 to 5, the numeral 1 indicates a folder which is adapted to have attached thereto a plurality of holders 2, each of which is adapted to support a plurality of index cards 3.

50 Each of the holders 2 is formed with a

plurality of angular slits arranged in vertically extending rows indicated at 4, 5 and 6. The angles of the slits of the rows 4 and 6 extend upwardly, while the angles of the slits of the row 5 extend downwardly. The slits of the rows 4 and 6 respectively provide rows of triangular tabs 7 and 8, the apexes of which are at their upper edges, while the slits of the row 5 provide a row of substantially triangular tabs 9, the apexes of which are disposed at their lower edges. The tabs 8, 9 and 7 are disposed in alignment horizontally of the holders 2, with the apexes of the tabs 9 substantially on a line with the bases of the tabs 8 and 7.

Each of the cards 3 is provided in spaced relation to the upper edge thereof with a horizontally disposed row of spaced slots 10, certain of which are adapted to lie in registry with the rows of tabs 7 and 8 when the card is in position on the holder. On the line of the slots 10, the card is creased transversely for coaction with the slots to provide a hinge line for the card. In the cards shown in Figures 1 to 5, the row of slots 10 is spaced from the upper edge of the card a distance substantially equal to the combined height of two adjacent tabs formed on the holders 2. In assembling a card with respect to a holder, a pair of horizontally aligned tabs 7 and 8 are inserted through the slots 10 in registry therewith, and the upper edge of the card is inserted under the tab 9 next above the line of the tabs 7 and 8 inserted through the slots. In carrying out the assembling of 75 the cards with respect to a holder, the lowermost tab 7 is inserted through the slot 10 in registry therewith, after which the card is swung upwardly to bring the upper edge thereof under the tab 9 located second from the bottom of the row, then a free marginal portion of the card is moved upwardly, then downwardly to insert the lowermost tab 8 through the slot 10 aligned therewith. The next card is then secured to the holder by 80 inserting the tabs 7 and 8 which are third from the bottom through the slots 10 of the card in registry with such tabs, and the upper edge of the card is inserted under the tab 9 which is fourth from the bottom. If desired, 85

90

95

100

the row of slots 10 may be spaced from the upper edge of the card a distance equal to the height of the tab on the holder, in which event the upper edge of the card will be inserted under the tab 9 which is in horizontal alignment with the tabs 7 and 8 inserted through the slots of the card in registry with such tabs 7 and 8. It is to be noted that the slots 10 form a part of the hinge means for 10 the cards, as well as a part of the supporting means therefor.

Referring to Figure 6, the card 11 shown therein is provided in spaced relation to its upper edge with a row of slots 12 similar to 15 the row of slots 10 in the cards 3, but with the outermost of the slots 12 spaced farther from the next adjacent slots than the remaining slots are spaced from each other. In alignment with the slots 12 the card is creased 20 transversely to provide a hinge similar to the hinge provided in the cards 3. The card 11 is further formed, midway between the row of slots 12 and the upper edge of the card with a pair of supporting slots 13 for 25 engagement with horizontally aligned tabs 7 and 8 on the holders 2 when the card is applied thereto. The slots 13 respectively are vertically aligned with the space between the outermost slots 12 and next adjacent slots, 30 centrally of such spaces. In the card shown in Figure 6, the slots 13 are spaced from the upper edge of the card a distance equal to the height of each tab of the holder, thereby bringing the upper edge of the card beneath 35 the tab 9 which is in alignment with the tabs 7 and 8 inserted through the slots 13. If desired, the slots 13 and 12 may be further removed from the upper edge of the card a distance equal to the height of one of the 40 tabs, in which construction the upper edge of the card will be inserted beneath the tab 9 next above the line of the tabs 7 and 8 inserted through the slots 13 when the card is in position on the holder.

45 It is thought that the many advantages of a filing system in accordance with this invention will be readily apparent, and although the system preferably will be constructed in accordance with the embodiments herein 50 illustrated and described, it is to be understood that changes in the details of construction may be resorted to, so long as such changes fall within the scope of the invention as defined in the appended claims.

55 Although the holders for the cards are illustrated in connection with folders, each containing a plurality of holders, the latter may be filed directly in a filing cabinet if desired. Also the holders may be indexed 60 in any suitable manner to provide for the ready selection of the proper holder when using the system. Likewise, while the holders are shown with top marginal portions thereof secured to the folder, the holders may 65 be provided at one side with a blank mar-

ginal portion to be secured to the folder if desired.

What I claim is:—

1. In a filing system, a holder of flat formation having a plurality of spaced rows of 70 tabs, the free edges of the tabs of one row extending in the opposite direction from the free edges of the tabs of the other rows, and a card supported on said holder, said card having its upper edge inserted beneath a tab 75 of such of said rows wherein the free edges of the tabs face in one direction, said card being slotted in spaced relation to its upper edge for receiving a tab of such of said rows wherein the free edges of the tabs face 80 in the opposite direction.

2. In a filing system, a holder of flat formation having a plurality of spaced rows of substantially triangular tabs, the apexes of 85 the tabs of one row extending in the opposite direction from the apexes of the tabs of the other rows, and a card supported on said holder, said card having its upper edge inserted beneath a tab of such of said rows wherein the apexes of the tabs extend in one 90 direction, said card being slotted in spaced relation to its upper edge for receiving a tab of such of said rows wherein the apexes of the tabs extend in the opposite direction.

3. In a filing system, a holder of flat formation having a plurality of angular slits providing a plurality of substantially triangular tabs, said tabs being arranged in vertical rows with the apexes of the tabs of one row extending in the opposite direction from the 100 apexes of the tabs of the other rows, and a card supported on said holder, said card having its upper edge inserted beneath a tab of such of said rows wherein the apexes of the tabs extend in one direction, said card being 105 slotted in spaced relation to its upper edge for receiving a tab of such of said rows wherein the apexes of the tabs extend in the opposite direction.

4. In a filing system, a holder of flat formation having a plurality of spaced rows of tabs, the free edges of the tabs of one row extending in the opposite direction from the free edges of the tabs of the other rows, and a card supported on said holder, said card 115 having its upper edge inserted beneath a tab of such of said rows wherein the free edges of the tabs face in one direction, said card being slotted in spaced relation to its upper edge for receiving a tab of such of said rows 120 wherein the free edges of the tabs face in the opposite direction, said card being transversely creased on its slotted line to provide a hinge.

5. In a filing system, a holder of flat formation having a plurality of spaced rows of tabs, the free edges of the tabs of one row extending in the opposite direction from the free edges of the tabs of the other rows, and a card supported on said holder, said card 125 130

having its upper edge inserted beneath a tab of such of said rows wherein the free edges of the tabs face in one direction, said card being slotted in spaced relation to its upper edge for receiving a tab of such of said rows wherein the free edges of the tabs face in the opposite direction, said card being slotted and creased on a transverse line in spaced relation to its tab-receiving slotted portion

10 to provide a hinge.

6. In a filing system, a holder of flat formation having a plurality of angular slits providing a plurality of tabs arranged in vertical rows with the tabs of the respective rows 15 horizontally aligned, and a card supported on said holder, said card being slotted in spaced relation to its upper edge for receiving a plurality of said horizontally aligned tabs.

20 In testimony whereof, I affix my signature hereto.

JAMES M. KEPLAR.
